FILM CHARGING DEVICE FOR USE WITH
CINEMATOGRAPHIC CAMERAS AND PRO-
JECTORSCharles Edward Hillary-Collings, London, Eng-
land, assignor to Camera-Projectors Limited,
London, England, a British companyApplication June 9, 1933, Serial No. 674,971
In Great Britain March 15, 1932

3 Claims. (Cl. 242—71)

This invention relates to film charging devices for use with cinematographic cameras and projectors, of the kind in which two similar trays are connected together by means of tongues cut out of the flat bottoms of the trays, the tongues on each tray fitting into the slots in the other tray left by the cutting of the tongues, each of the trays having an opening through which the film could be wound from a spool in one tray on to a spool in another tray.

According to the present improvement, the tongues which are located in diametrically opposite positions on the tray bottoms, each tongue being spaced 90 degrees from the centre of the film openings in the two trays when united, or from a point midway between the extreme limits of the two openings when they are not coincident are so placed that the two trays can be united by relative rotation instead of sliding one diametrically on to the other.

In order that the said invention may be clearly understood and readily carried into effect, the same will now be described more fully with reference to the accompanying drawing wherein Figures 1 and 2 represent in plan the upper and lower trays in one example of the application of the invention.

Figures 3 and 4 represent in plan upper and lower trays in another example.

Figure 5 is an elevation of the two trays represented in Figures 3 and 4.

It will be understood that in use the coupled trays may be either side by side in a vertical position, or superimposed in a horizontal position as shown in Figure 5.

In the form shown in Figures 1 and 2, A indicates the upper tray which is provided with tongues a^1 and the film opening a^2 , while B indicates the lower tray having tongues b^1 and the film opening b^2 . The outer faces of the trays may be cut away as shown at a^3 and also have openings a^4 which expose only such portions of the tray thus revealed to wear and tear, the thickness of the outer faces of the tray A in this form thereof tending to partly protect the tongues from blows or accidental contact with objects, while the tongues in the opposite trays nevertheless project sufficiently to mutually engage each other. Openings a^4 render visible the tongues a^1 formed in the inner faces when the trays are empty.

In the other form of the trays shown in Figures 3 to 5, the trays C and D have tongues c^1 and d^1 similar to tongues a^1 and b^1 of the first mentioned trays A and B. As may be noted particularly in Figure 3, the cut out portion c^3 may

be considerably narrower in tray C than the cut out portion a^3 of tray A.

The trays made according to either form of the invention are placed in contact and the upper tray rotated in the direction indicated by the upper arrow seen in Figure 1 to bring the tongues into engagement.

In Figures 1 and 2, the film opening of the upper tray is of the same width as the film opening of the lower tray and directly above the latter opening. The base or widest part of each tongue a^1 and b^1 is located on a radial line at right angles or 90° to the radial line from the centre of the tray to the centre of the film opening. Tongues a^1 and b^1 are thus disposed on a radial line in each case.

In Figures 3 to 5, where the film openings c^2 and d^2 are staggered, the roots of the tongues c^1 and d^1 are located on a radial line at right angles to the radial line from the centre of the tray to the meeting point of the two openings.

The trays are partly rotated together when they are to be superimposed, and due to the fact that the tongues on each tray are directed in the same direction of rotation, the trays will accurately register in mutual juxtaposition when the tongues in one tray engage those in the other.

The tongues may be of semicircular or other suitable rounded shape instead of being pointed as shown.

The improvements are applicable to pairs of trays for winding on and off film for projection which is not sensitive and for which it is not necessary to provide both inner and outer trays.

What I claim and desire to secure by Letters Patent of the United States is:—

1. In a film charging device for use with cinematographic cameras and projectors, said device comprising two circular trays having flat bottoms, a pair of tongues partly cut out in each of the said flat bottoms, said tongues facing in opposite directions and leaving slots in said flat bottoms, the widest part of each of said tongues and slots being located on a radius of the tray, the tongues on each tray being adapted to register in the slots in the other of said trays when the two trays are juxtaposed and relatively rotated to bring their respective tongues and slots into absolutely accurate engagement with respect to the centers of said trays, so that both trays are accurately superimposed and are thereby adapted to simultaneously fit perfectly in position upon said cameras or projectors and thus prevent leakage of light into the same past the circumferential edge of either of said trays.

2. A device according to claim 1 having film exit and inlet openings formed in the annular walls of the two trays, which openings are out of alignment with each other when the trays are united, while the widest part of each tongue is spaced about 90 degrees from the joint centre of said openings when the trays are united. 80

3. A device according to claim 1 having film
